JOHN E. CLARK, OF KANAWHA COUNTY, WEST VIRGINIA, ASSIGNOR TO THE CLARK
PAVING CORPORATION, OF NEW YORK, N. Y., A CORPORATION OF DELAWARE.

COMPOSITION ROAD-SURFACING AND METHOD OF LAYING SAME.

1,364,036.

Specification of Letters Patent. Patented Dec. 28, 1920.

Application filed October 30, 1914. Serial No. 869,484.

To all whom it may concern:

Be it known that I, JOHN E. CLARK, a citizen of the Dominion of Canada, residing in the county of Kanawha, State of West Virginia, have invented new and useful Improvements in a Composition Road-Surfacing and Method of Laying Same, of which the following is a specification.

This invention relates to pavements and 10 the method of laying the same.

One object is to provide a pavement having durable wearing qualities either in cold or warm weather or climates and which is not subject to cracking incident to vibration 15 due to heavy traffic and whose edges, when disposed adjacent railroad tracks, are so formed as to obviate cracking and deterioration incident to vibration caused by the rolling stock.

Another object resides in the provision of 20 a pavement whose wearing surface is cushioned and whose cushioning means is supported upon a foundation layer above the line of dampness with said supporting 25 means for the cushioning means being constructed to provide for the circulation of air and for drainage.

Another object resides in the provision of 30 a flexible, noiseless, sanitary, moisture-proof, dustless, and non-slippery pavement or the like composed for the most part of waste products.

Another object is to provide an inexpensive yieldable and durable pavement whose 35 wearing surface is yieldably supported or cushioned and whose cushioning or yieldable supporting means is composed of waste material, and which may be reinforced at points where subjected to unusual vibration 40 as, for instance, railway rolling stock, so as to prevent undue deterioration of the wearing surface adjacent the railroad tracks.

A still further object is to provide a pavement embodying among other characteristics 45 structural features which provide for drainage both from above and below the wearing surface so as to overcome dampness and thereby obviate one of the serious defects or causes which attack and impair the 50 life of pavements.

A still further object is to provide a pavement or the like consisting of superimposed layers of fibrous material, one of 55 which has a higher point of penetration than the other.

It is still further designed to provide a pavement embodying layers composed of waste vegetable fibrous material with one layer composed of longer fiber than the other and supported over means providing 60 for the circulation of air and drainage beneath the layers, and with the layers forming substantially an umbrella over said supporting means to prevent seepage through the pavement.

With the above and other objects and characteristics in view, the present invention consists in the combination and arrangement of materials and elements hereinafter more fully described, illustrated in the accompanying drawings, and particularly pointed out in the appended claims, it being understood that changes may be made in the materials, proportions, size and minor details without departing from the spirit or 75 sacrificing any of the advantages of the invention.

In the drawings:

Figure 1 is a view of a pavement constructed in accordance with my invention, 80 showing the same partly in transverse section.

Fig. 2 is a transverse view of the curbstone.

Referring now more particularly to the 85 accompanying drawings, the reference character 1 indicates the road foundation formed in any suitable manner, at the edges of which may be disposed curbstones 5. Each curbstone is composed of any suitable material and preferably provided with a longitudinal internal gutter 6 provided at its lower portion with a plurality of openings 6' which lead inwardly of the respective curbstone adjacent the upper surface of the 95 foundation 1. Other openings 7 are formed in each curbstone 5 and extend from the respective gutter 6 to and through the inner face of the curbstone above the aforesaid openings for a purpose presently explained. 100

The characters *a* and *b* indicate railroad rails which may be mounted upon the foundation 1 in any suitable manner. Layers 2 of broken stone may be laid upon the foundation 1 between the curbstones and the 105 rails and between the rails. These layers 2 preferably consist of loose stones whose interstices or voids are preferably not filled so as to permit the circulation of air and the drainage of any water or moisture which 110

may find its way into the layers of broken stone. Drainage is permitted from the layers of stones through the apertures 6' into the internal gutters 6 and, by virtue of air 5 passing through the gutters 6, the moisture is readily evaporated and an efficient and speedy drying out effected in the layer of stone if dampness occurs.

A layer 3 of fibrous material is disposed 10 on each layer of broken stone. This fibrous material may consist of straw, cotton stalk, sugar cane, or any other suitable fibrous material which is preferably shredded and long in length. Before laying this fibrous 15 vegetable matter, it is preferably boiled or cooked for a sufficient length of time to render it soft and pulp-like and is then subjected to the action of hot asphalt or bitumen to insure a thorough impregnation of 20 the fiber with the asphalt or bitumen and thereby provide for an effective binding and preservation of the fiber. The material being impregnated when coming into contact with the hot binder and preservative creates 25 steam which arises from the surface and pores of the fiber and facilitates the thorough impregnation of the fiber with the binder or preservative.

The denatured material thus formed and 30 composing the layers 3 is flexible and preferably laid on the foundation 1 while in a hot state and after being laid on the foundation and while hot, it is preferably rolled by a steam roller or otherwise and thereby compactly compressed on the stone layers 2. Before the layers 3 are placed on the layers 2 the webs of the rails between the base flanges thereof and the underside of the tread surface and also the inner faces of the curbstones 35 may be painted with bitumen or other adhesive material, with the result that, incident to the compression of the layers 3 on the layers 2 by the rolling action, the edges of the fibrous layers 3 are caused to adhere 40 to the curbstones and to the rails. The layers 3 include substantially sixty-six and two-thirds per cent. long coarse graded straw by weight to substantially thirty-three per cent. and one-third asphalt or other binding 45 and preserving agent of preferably not less than fifty-five penetration point.

Layers 4 of fibrous material are preferably laid on the layers 3. These fibrous layers 4 are preferably formed of the same material as the material of which the layers 3 are formed, but are preferably composed of short fiber, as distinguished from the longer fibers of the layers 3. This short fiber of which the layers 4 are formed is treated in 50 the same manner as the fibers of which the layers 3 are composed.

While the material is in a state of porosity, a sufficient amount of asbestos is added to render said layers 4 fire proof. The layers 4 55 preferably include substantially forty per

cent. of asphalt to sixty per cent. short graded fibers mixed with the fireproof material, the asphalt being preferably not more than forty-one point penetration. By virtue of the long fibrous material of the layers 3 70 being impregnated with a binding and preservative agent of a very high point of penetration they are rendered soft and retain softness or pliability in cold weather, and being covered by the upper or surface layers 75 4 of harder and less pliable nature, they are protected from the hot sun and do not become mushy and therefore do not lose their requisite cushioning effect for the upper layers 4. 80

While in a hot condition the surface layers 4 are laid on the layers 3 and rolled. The fireproof material also assists to bind and fill the voids in the wearing surfaces 4 when the same is subjected to pressure incident to 85 the rolling operation. The rolling pressure on the surface layers 4 causes the short fibers of the same to fill the voids in the layers 3 and thereby effect a firm and substantial locking or binding of the layers 3 and 4 together which prevents slipping of the surface layers 4 on their cushioning layers 3. The wearing surface of the layers 4 is preferably disposed adjacent the line of the upper openings 7 in the curbstones so that 95 drainage may be permitted from the surface of the roadway through the apertures 7 into the internal gutters 6.

If desired, the upper surfaces of the rocks forming the base layers 2 may be painted 100 with bitumen, cement or other suitable material so as to facilitate binding of the layers 3 thereto and, if desired, the upper surfaces of the layers 3 while hot may be likewise painted so as to facilitate binding of the 105 surface layers 4 to the latter. In any event, the short fibers of the surface layers, and the painted solution, if used, fill the voids, if any, in the layers 3 when compressed or rolled. 110

By virtue of vibration incident to passage of rolling stock over railroad rails there is a tendency in concrete and other pavements to crack along the rails. I overcome this objection in pavements by rendering the intermediate or cushioning layers 3 relatively thick at their edges where they engage the rails, as shown, extending this thickness in the material out from the rails beyond the point of vibratory action on the pavement 115 120 caused by the rolling stock passing over the rails. I may also reinforce the fibrous cushioning layers 3 along the sides of the rails. One way in which this reinforcing may be accomplished is to provide metallic elements 125 8 of any suitable character which are preferably embedded in the fibrous layers 3 and which extend outwardly away from the rails slightly beyond the point of vibration on the pavement. 130

5 Of course, where the pavement is laid in roadways over which railroad rolling stock does not pass, the layers 3 and 4 may be formed in sheets entirely across the roadway from curb to curb and it will also be understood that instead of laying a roadway in sheets, the same may be laid in block form and that the material of which the roadway is composed is equally applicable to the 10 building or covering of walls of buildings.

10 It will be understood that, by virtue of the layers 2 being composed of loose stone or rocks that they do not close the openings 6 leading to the gutters 6 in the curbstones 15 5 and that if water, incident to frosts, rains, snows or the like should seep into the pavement adjacent the tracks, or curbstones, such seepage and consequent moisture would be drained out from under the pavement by 20 reason of its percolation through the loose stones into the gutters 6. It will be understood also that all water remaining on the surface of the surface layers 4 will find its way off of the pavement by way of the upper 25 openings 7 into the gutters 6 with the result that the pavement is drained from both above and below the wearing surface and that, therefore, the pavement is relieved of 30 its greatest injurious factor or agent, for when proper drainage is not provided for, or when moisture and water incident to frosts, rains, snows, etc., is permitted to remain in the under-surface of a pavement and therein mold, there is a consequent untimely and undue deterioration of the pavement.

35 Under certain conditions pavements may be built without the layer base 2 of stone. In some localities it is impossible to get 40 gravel, stones or the like except at great expense because of distance the same must be transported. There are times when the traffic is light and the base layer of stone is not needed, and furthermore, the curbstones 45 may be eliminated. To this end the layer of long fibrous material may be placed upon the foundation 1 and the surface layer disposed on the layer of long fibrous material. Especially where railroad tracks are 50 not disposed in the roadway or street, and when the layers are built in continuous sheet form, the very nature of the layers incident to the aforesaid treatment and method of laying one layer on the other results in the 55 layers serving practically as an umbrella over the foundation of the roadway, thereby excluding water incident to frosts, rains, snows or the like from the foundation and thus insuring dryness beneath the pavement.

60 What is claimed is:

1. In a roadway, curbstones disposed along opposite sides of the roadway, each curbstone having an internal gutter provided with a plurality of openings which 65 open inwardly of the respective curbstone

and above the foundation of the roadway and each of which gutters also has a plurality of openings above the aforesaid openings and which lead through the inner side of the respective curbstone, a layer of 70 broken stone disposed on the foundation of the roadway, and a layer of fibrous material disposed on the layer of broken stone with the upper surface thereof below the uppermost openings of the curbstones whereby 75 drainage is permitted from above and below the wearing surface of the roadway.

2. A pavement consisting of a base layer composed of loose rock, a cushioning layer composed of long fibrous material impregnated with a binding and preservative agent and a surface layer including short fibrous material impregnated with a binding and preservative agent, the whole being compacted together under suitable pressure so 80 that the short fibers of the surface layer fill the voids of the cushioning layer and lock the impregnated, fibrous surface layer and the impregnated cushioning layers together, the base layer of rock affording drainage toward 85 both sides of the pavement from below the surface layer.

3. In a roadway, curbstones disposed along opposite sides of the roadway, each curbstone having an internal gutter provided with a plurality of openings which open inwardly of the respective curbstone and above the foundation of the roadway and each of which gutters also has a plurality of openings above the aforesaid openings and which lead through the inner side of the respective curbstone, a layer of 90 broken stone disposed on the foundation of the roadway, a layer of fibrous material disposed on the layer of broken stone, and a 95 surface layer of fibrous material disposed on the aforesaid layer of fibrous material with the wearing surface thereof below the uppermost openings of the curbstones whereby 100 drainage is permitted from above and below the wearing surface of the roadway.

4. A pavement comprising a layer composed solely of long fibrous material impregnated with a binding and preservative 115 agent, and a layer of short fibrous material impregnated with a binding and preservative agent, said layers being compacted together under suitable pressure so that the short fibers of the surface layer fill the voids 120 between the long fibers of the first named layers and lock the two layers together.

5. A pavement consisting of a foundation, railroad tracks on the foundation, layers of rock between the tracks and between the 125 tracks and the side edges of the pavement, and layers of fibrous material compressed on the layers of rock material, the layers of fibrous material adjacent the tracks being thickened.

6. A pavement consisting of a foundation, railroad tracks on the foundation, layers of rock between the tracks and between the tracks and the side edges of the pavement, 5 layers of fibrous material compressed on the layers of rock material, the layers of fibrous material adjacent the tracks being thickened, and surface layers of fibrous material disposed on the aforesaid layers of fibrous 10 material.
7. A pavement consisting of a foundation, railroad tracks on the foundation, layers of rock between the tracks and between the tracks and the side edges of the pavement, 15 layers of fibrous material on the layers of rock material, the layer of fibrous material adjacent the tracks being thickened, surface layers of fibrous material disposed on the aforesaid layers of fibrous material, and 20 means for reinforcing the first named fibrous layers of material at their thickened portions.
8. A pavement consisting of a base material, railroad tracks having adhesive material 25 on the sides of the tracks, layers of fibrous material between the tracks and on opposite sides thereof and connected to the tracks by said adhesive material, the layers of fibrous material adjacent the tracks being thickened, and surface layers disposed on the layers of fibrous material.
9. A pavement consisting of a base material, railroad tracks having adhesive material 35 on the sides of the tracks, layers of fibrous material between the tracks and on opposite sides thereof connected to the tracks by said adhesive material, the fibrous material adjacent the tracks being thickened, surface layers disposed on the layers of 40 fibrous material, and means for reinforcing the fibrous layers at their thickened portions.
10. A pavement comprising a layer composed of relatively long graded fibrous material impregnated with a binding and preservative agent, and a layer of relatively short graded fibrous material impregnated with a binding and preservative agent, said layers being compacted together under suitable pressure so that the short fibers of the 45 surface layer fill the voids between the relatively long fibers of the first-named layer and lock the two layers together.
11. In a pavement, a layer of relatively long fibrous material impregnated with a 50 binding agent in combination with a layer of relatively short fibrous material impregnated with a binding agent and fireproof material, said two layers being compacted together by pressure so that the short fibers 55 of the one layer will fill the voids between the long fibers of the other layer and lock the two layers together.
12. A pavement consisting of a base layer of loose rock, a cushioning layer composed 60 of relatively long fibrous material impregnated with a binding agent and superimposed on the layer of loose rock in combination with a layer of relatively short fibrous material impregnated with a binding 65 agent and fireproof material and superimposed on the cushioning layer, said layers being compacted together under pressure so that the short fibers of the surface layer will fill the voids between the long fibers 70 of the cushioning layer and lock the whole 75 pavement together.

In testimony whereof I affix my signature in the presence of two witnesses.

JOHN E. CLARK.
